INSULATING BOX

Virginius W. Moody, Long Branch, N. J., assignor
to Reynolds Research Corporation, New York,
N. Y., a corporation of Delaware

Application July 11, 1932, Serial No. 621,875

6 Claims. (Cl. 217—5)

This invention has to do with a box or container for maintaining a predetermined temperature, and relates more particularly to a box or container having a plurality of walls of graduated dimensions, those of greater dimension being in sealed assembly to envelop those of smaller dimension in a manner to leave an air space between the walls.

An object of the present invention is the provision of a box for the preservation of a desired temperature and comprising a series of enclosures, one member being enclosed by the next larger, the walls of said enclosures being supported in separated opposed relationship.

Another object of the present invention is to provide a new and novel frame for the support of panels to effect a box or container of the character described.

Another object of the present invention is to provide a frame such as the above and held in assembly by an improved form of splined pin.

Another object of the present invention is to provide a box for the preservation of a desired temperature and comprising walls of panels in opposed relationship, there being a void between said panels and a support for each of said panels coextensive with the edge thereof.

Still another object of the present invention is to provide, for enclosing a space, walls of a laminated structure, there being voids intermediate said laminations and a bright metallic surface exposed by said laminations.

With the above objects and other desirable objects in view, the invention is hereinafter set forth with reference to the accompanying drawings hereby made a part of the specification and in which:

Figure 1 is a central cross section of one form of the invention;

Figure 2 is a sectional view of the form of the invention illustrated in Figure 1 and taken along the line 2—2 of that figure;

Figure 3 is a view in perspective of a corner of a box as illustrated in Figures 1 and 2, panels being removed from a side thereof to show details of frame structure therefor;

Figure 4 is a fragmentary sectional view of a form of the invention having a frame of a laminated character;

Figure 5 is a fragmentary sectional view of a form of the invention in which the panels are disposed intermediate the elements of laminated frame members;

Figure 6 is a sectional view of the form of the

invention shown in Figure 4 taken along the line 6—6 of such figure;

Figure 7 is a view of the form of the invention illustrated in Figure 5 and taken along the line 7—7 of that figure;

Figure 8 is a central cross section of a different form of the invention;

Figure 9 is a fragmentary view of a form of the invention taken along the line 9—9 of Figure 8;

Figure 10 is a fragmentary sectional view of the form of the device shown in Figure 8 and taken along the line 10—10 of said figure;

Figure 11 is a fragmentary sectional view of a different form of the invention;

Figure 12 is a fragmentary sectional view of a form of the invention slightly modified from the form shown in Figure 11;

Figure 13 is a fragmentary view of the form of the invention shown in Figure 12 and is taken along the line 13—13 of that figure; and

Figure 14 is an orthographic projection of the form of the invention shown in Figures 12 and 13 and taken on the line 14—14 of Figure 13.

Like reference characters indicate similar parts in the drawings and throughout the following description of the invention.

Each of the embodiments of the invention herein described comprises the equivalent of a series of boxes, parallelepiped in shape, with one supported within the other and each being supported along the twelve corners thereof formed by the intersection of adjacent faces.

Reference to Figures 1, 2 and 3 will first be had. In Figure 1, as a part of a frame 10 for the device, are four ribbed members 11 in cross section transverse to ribs or steps 12 therein. The frame members 11 are identical and are of the configuration of a trapezoid, the shorter of the two parallel edges being disposed along a corner 13 formed by the joinder of two sides 14 of an interior cabinet 15.

Connected to the diagonal edges of the members 11 shown in cross section in Figure 1 are other members 11 angularly exposing a stepped 45 face thereof. The diagonal edges of the generally plane-like members 11 are beveled so that the diagonal beveled edge of each of said frame members fits regularly into engagement with the similarly treated edge of the two other members, 50 the longitudinal elements of each member being at right angles to those of the other two members.

Four frame members 11, not shown in the sectional view, Figure 1, are opposed to the members shown in side view there and join the oppo- 55

site ends of the members 11 shown in cross section in exactly the same manner as do the first mentioned members 11.

The frame of the form of the invention illustrated in Figure 1 appears as a six-faced figure with each of its six faces configuring the low relief of a four sided truncated pyramid. Each of the six faces then embodies a cavity with a plurality of steps encircling its walls. The side 10 of each frame member 11 has steps 12 upon both sides. These steps are so arranged that those upon each frame member register at their extremities with others at right angles thereto and upon the adjoining members. Thus each face 15 of the entire frame exposes a group of continuous steps 12 offset from the next, the concatenation reaching to the outer edges of said face.

The diagonal edge of each of the members 11 may be scored with a tenon groove 16 coextensive 20 with the length of said edge. When three of these edges are brought together in the process of forming the frame, a splined tenon member 17 having three protuberances 18 is brought into coengagement with the frame members by means 25 of the grooves 16. The splined member 17 in this manner provides a dovetail joint between the three frame members to lock them in place. With such a construction at each of the joining edges of the frame members, the frame is made 30 into a strong and rigid structure.

With the frame of the device in assembly as above described, the cabinet 14 is placed therein. It will be observed in Figure 1 that grooves 19 are cut within the lower of the inwardly exposed 35 edges of the trapezoidal frame members 11 to form a seat for the lower corners of the cabinet.

An opening conforming to a horizontal section of the cabinet 15 is configured by the inner adjoining edges of the upper members 11 to facilitate the insertion of the cabinet from that side. After the cabinet is seated upon the lower members 11, and between the side members 11 similarly engaging the vertical corners of the cabinet, a rectangular frame 20 is brought into position 40 cocontiguous with the top face of the cabinet and the inner edges of the upper frame members 11. By fastening the frame 20 into such position to the adjacent members 11, it serves as a stop to the egress of the cabinet, hence the cabinet is 45 securely held within the frame and against movement in any direction.

Subsequent to the placing of the cabinet 15 within the frame 10, panels 21 are attached to the sides of the frame. The panels 21 consist of 50 any strong heat insulating sheet material and are cut rectangular or square, as the case might be, to fit snugly into the stepped recesses of progressive circumference. The extent of the faces 22 of the steps 12 determines the breadth of the voids between the panels. Panels of a smaller area are secured to the steps nearer the interior 55 of the frame by any standard means such as by tacking, or by a suitable adhesive. The area of the panels is increased in accordance with the increase in perimeter of the stepped surfaces as the exterior of the frame is approached. The outermost panels within the sides of the frame may be covered by a thick protective panel 22a.

As an impediment to the transfer of radiant 70 heat through the box walls, a bright metallic material may be applied to each of the opposed flat surfaces of the panels 21. Since the voids between the panels are insulators to the conduction of heat as are the frame members in 75 support of the panels, the walls of the box pre-

clude the transfer of heat either by conduction or by radiation.

The third manner by which heat is conveyed, namely convection, is greatly overcome by the arrangement of the series of voids for the reason 5 that the differences of temperature subjected to opposite sides of the voids is not sufficient to cause a turbulation of the air therein. Further, the shape of the voids is averse to an agitation of cumulative effect of the air.

Access to the cabinet is had by way of an opening 23 in the top side of the box. An aperture 24 in the top side 14 of the cabinet 15 is in alined relationship with similarly shaped holes 24a in the panels 21 thereabove. Usually it is desired to 15 uniformly increase the size of the holes in the panels coforming the opening 23 as the panels approach the exterior, so that a door frame member 25 will be on a slant to contain a door in a wedge-like manner.

The door frame member 25 and the door therefor, not shown, are ordinarily of a heat insulating material. Panels not unlike those in the box walls may form the body of the door to cause it to have the same heat transfer characteristics as 25 the walls of the box for the inclusion or exclusion of heat in or from the box.

Figures 4 and 6 illustrate a box with a frame structure somewhat modified in respect to that illustrated in the three lower numbered figures. 30 The opposite faces of the plane-like frame members 25a are formed of laminated elements 26, the laminations 27 in one of the elements lying normal to those in the other. By uniformly increasing the breadth of the laminations 27, these 35 being of wood or other strong heat insulating material, from a common base line, the steps 28 are provided to accommodate the laying of the panels 29. Panels 29 are secured to the steps in the manner before described and may include in 40 their structure bright metallic faces.

It will be noted that the mode of assembly here employed brings the frame members together flatly to dispense with the operation of beveling the adjoining edges thereof. The material of the 45 frame members is not in this case equally divided by a plane likewise dividing the frame member diametrically opposite but rather the opposed frame members are set on opposite sides of such a plane.

The form of the device shown in Figures 5 and 7 is assembled very similarly to the next preceding form which has been described. Laminations 35 of a heat insulating material enjoin the frame members 36. In this form, however, the 55 panels, instead of abutting against the step face provided by the next outward lamination, are assembled intermediate the laminations. There is no bright metal foil applied to the part of the panels incorporated into the frame structure. If such were the case, a heat conductive path would be established from the exterior of the box to each of the wall voids to defeat in part the purposes of the box. In this form, where the panels are 60 fabricated with the frame members, the metallic surface is only applied to the portions of the faces lying between the frame parts.

Another modification of the box is illustrated in Figures 8, 9, and 10. This form is similar in its 70 construction to that illustrated in Figure 1 and differs therefrom only in that the number of frame members is increased. Diagonal frame members 40 are trapezoidal in shape and have grooves in parallelism to the two parallel edges 75

thereof to configure steps 41 for the placement of panels 42 adjacent the latter's edges.

In cosupport of the frame members 40 along their cornered edges is a storage cabinet 43.

- 5 Extending perpendicularly from a central position of the faces of the cabinet 43 are other trapezoidal shaped frame members 44 having steps both upon the sides and the ends thereof. The steps on the ends of the frame members 44 engage 10 the steps upon the perpendicular members 40 as shown at 44a Figure 9. Panels 42 are divided into four parts or quadrants by the frame pieces 44, two edges of the divided members being held in position by a step of the intersecting members 15 44, the opposite edges thereof being supported by a selected step in the opposed frame members 40 in a manner to hold the panels parallel to the adjacent face of the cabinet 43.

The top side of the box may contain a block of 20 wood or molded heat insulating material as a door casing 45. Steps or notches 46 in the lateral edges of the casing 45 serve to support the edges of the panels 42 within that box side. An opening 48 communicating to the interior of the cabinet 25 through an opening 49 within the cabinet wall is shaped like the frustum of a rectangular pyramid with the opening walls converging inwardly.

The walls of the opening 48 may be fitted with 30 a gasket 50 circumscribing thereof, and the door 51 to fit into the opening 48 may have a gasket 52 therein so that when the door is closed against the gaskets, an air space will be formed between the said gaskets.

35 A box very similar to that shown in Figure 4 is shown in Figure 11. The latter mentioned figure illustrates a form of the invention in which the diagonally arranged frame members 60 are of a solid structure instead of being fabricated from 40 flat pieces of material of a selected thickness. The members 60 at two opposite sides of the box, and providing steps 61 for panels 62, are displaced from a centered corner position toward 45 one another to aline one stepped face thereof with said centered corner.

Figures 12, 13, and 14 disclose a form of the invention having frame members 70 and 71 of 50 solid heat insulating material such as wood and which may be assembled with the side panels 72 and 72a respectively before the frame members are completely assembled with one another. For example, four members 70 may be assembled into a four-sided window with the panels 72 placed and secured to the steps 73 thereon. Four of 55 these figures, each being formed of four of the members 70, may then be fastened into position to comprise four sides of the box in much the fashion of a four-sided prism with the ends open. The other parts 71 are then assembled with the 60 panels 72a to form the closures for the remaining two sides or ends of the box. The two opposite ends of the box made from the frame members 71 are of smaller dimensions than the other sides of the box and telescope into the end 65 openings.

A heavy panel 74 is inserted between the members 71 to rest flush with the inner edge thereof. Similarly, a strong panel 75 is encircled by the inner edge of the frame members 70. When completely assembled, the panels 74 and 75 and the 5 inner face of the frame members 70 and 71 effect a smooth lining for the box. An opening 76 may be provided within one of the sides of the box in an identical manner as heretofore described.

Although the invention has been described in 10 several different forms and employing a polished metal surface as an element for retarding heat radiation, it is to be understood that any surface having a low factor of emissivity may be substituted therefor.

15 All forms of the invention have the advantage of having the space between each pair of opposed panels sealed and isolated from the other spaces similarly sealed. Each cube-like structure contained within the other is enclosed by six independent air spaces rather than by a single air space as would be the case if independently assembled boxes were supported one within the other by means of engagement at the eight corners. The factor of loss of insulating efficiency 20 due to injury or faulty workmanship is then minimized in a ratio of six to one.

25 What is claimed as new and is desired to be secured by Letters Patent of the United States is:

1. In an insulated cabinet, a wall comprising 30 a frame member about each edge thereof, each frame member being obliquely angular to the face of the wall and coextensive with the thickness thereof, and having parallel longitudinal steps therein, the steps on adjacent frame members 35 being aligned to provide a series of seats of graduated size, and a sheet of insulating material upon each of said seats.

2. The wall structure described in claim 1, and in which the wall has four frame members with 40 mitered ends.

3. The wall structure described in claim 1, and in which the frame members have mitered ends, and each frame member is common to two walls.

4. The wall structure described in claim 1, and 45 in which the frame members are wide relatively thin members having steps on opposite sides thereof.

5. In a parallelepiped shaped cabinet having 50 walls, members at each edge thereof and forming a frame, four of said members defining each side of said cabinet, and each of said members being at an angle of forty-five degrees to the surface of the adjacent walls.

6. In a parallelepiped shaped cabinet having 55 walls of sheet material, members at each edge thereof and forming a frame, four of said members defining each side of said cabinet, each of said members being at an angle of forty-five degrees to the surface of the wall supported by it, 60 and having steps therein, the steps of adjacent members being in alignment, and sheets of insulating material upon said steps.
